TAIL FOR FISHING LURE

William F. Stembridge, East Point, Ga., assignor to Stembridge Products, Inc., East Point, Ga., a corporation of Georgia

Filed June 29, 1961, Ser. No. 65,764

Term of patent 14 years

(Cl. D31—4)

Fig. 2

Fig. 3

Fig. 4

Fig. 5

FIG. 1 is a side elevational view of a tail for fishing lure, showing my new design.

FIG. 2 is a top plan view thereof.

FIG. 3 is an enlarged cross-sectional view taken on the line 3—3 in FIG. 1.

FIG. 4 is an enlarged cross-sectional view taken on the line 4—4 in FIG. 1.

FIG. 5 is an enlarged cross-sectional view taken on the line 5—5 in FIG. 1.

The dominant features of my design reside in the portions shown in full lines.

I claim:

The ornamental design for a tail for fishing lure, substantially as shown and described.
